PRESS BED LOCK-UP

William H. Ritenour, Pittsburgh, Pa.

Application May 4, 1933, Serial No. 669,345

1 Claim. (Cl. 101—394)

This invention relates to improvements in devices and methods for imposing and locking a type-form for printing purposes.

One of the objects of the invention is to provide locking means whereby the type units may be originally imposed and locked directly on the press-bed, without the usual preliminary "stone" lock-up.

A further object is to provide a printer's chase 10 that cannot be sprung out of shape by normal use.

A further object is to provide a printer's chase in which the type units may be automatically aligned.

A further object is to provide a printer's chase 15 that corresponds in its divisions according to the size of the sheet employed in working the job.

A further object is to provide a novel form of spacing material for forming the chase gutters which cannot work-up during the printing operation.

Additional objects will be readily discerned, or pointed out, hereinafter.

Heretofore it has been the universal custom to impose the type-pages of a book inside of a chase 25 located on the top of a table known as "the stone." The loose type-pages are lifted from their storage galleys and inserted in the form according to their impositional sequence and, since an ordinary book form embraces at least a thousand 30 separate and distinct lines of type which may be easily transposed in handling, a "stone proof" is generally pulled and carefully checked before the chase is finally locked and sent to press. The work is such that it calls for the best skill in the printing craft. My invention eliminates the "stone" lock-up entirely.

The excessive quoин pressure that is necessary in the final stone lock-up in order to make portable the inherently inaccurate elements—found in 40 every type-form—will invariably cause a distortion of the chase bars—in some type-forms as much as a pica. Accordingly, it has heretofore been the universal custom among pressmen, when a form is placed on the press-bed, to release the 45 quoин pressure (originally exerted at the stone from the inside of the chase) before squeezing the press clamps against the outside of the chase. But this procedure will not restore any great degree 50 of accuracy to the form and the resultant imperfect line-up in the printed sheet may be corrected only by a costly and laborious rejustifying of the form on the press-bed to fit a master position sheet. My invention automatically lines up each page on its four sides and provides a

chase in which the working dimensions are precise and unalterable.

Heretofore it has been necessary, after the required number of impressions have been printed, to again tighten the quoин pressure and remove 5 the form to the stone for the make-over into succeeding type-pages. My invention provides means and method whereby an entire new form may be imposed and locked directly on the press-bed in less time than a unitary portable form may 10 be merely removed and replaced.

Heretofore, considerable difficulty in printing from type-forms has been caused by the work-up of gutter spacing material. A reduced press speed, compared with that used for printing from 15 plates, has generally been found necessary. My invention provides means whereby the gutters are interlocked against work-ups and permits a maximum press speed without work-ups.

In the drawings—

Figure 1 is a plan view showing a separable chase structure and a layout of thirty-two type-pages;

Fig. 2 is a fragmentary enlarged view showing the imposition of the two type-pages represented 25 in the lower right-hand corner of Fig. 1;

Fig. 3 is an enlarged fragmentary plan view of a portion of the chase shown in Fig. 1;

Fig. 4 is an enlarged sectional view through 4—4 of Fig. 3;

Fig. 5 is a perspective view of my slug-page, shown assembled and ready for imposition on press-bed;

Fig. 6 is a detail perspective view of one of the justifying strips used in connection with the chase 35 to form the marginal gutters;

Fig. 7 is a detail perspective view of a modified form of justifying strip;

Figs. 8, 9 and 10 are similar views of still further modified forms of justifying strips;

Fig. 11 is a plan view of the bed of a flat-bed printing press, showing my chase locked thereon.

The chase

An individual outfit of separable steel bars 25a, 45 25b, 26a, 26b, 27a, 27b, 28a, 28b, 28c, 29a, 29b, 29c, 29d, 29e, 29f, as shown in Fig. 1, is preferably provided for each sheet size.

The three long cross bars 28 and the six short cross bars 29 are arranged against the two head 50 bars 27 in such dimension as to conform with the width of the sheet it is desired to print, as follows: The long cross bars 28a, b, c should be formed, in length, to correspond to one half of the width of the particular size of sheet it is 55

desired to work with this individual size of chase. Thus, when jointed with head bars 27a, b the dimension from the center of head bar 27a to center of head bar 27b, as shown on the line 27—27, Fig. 1, is exactly one-half of the given sheet width. (This is an important feature of the invention and does not pertain to mere dimension alone. It enables the impositor, without previous detailed calculation, to assemble a chase structure in which the sections (lock-up groups), formed by the bars, conform exactly to the folds in the subsequently printed sheet. In the usual form of chase, these sectional divisions are formed by careful and laborious adjustment of bars and printers' spacing material, and no actual division of the chase structure itself has heretofore been provided beyond an approximate positioning of the head bars.) The six short cross bars 29a, b, c, d, e, f, which adjoin the two-page groups, may be formed longer than their proportionate sheet-width dimension, since their length manifestly does not affect the folded divisions of the printed sheet. The three long cross bars 28 and the six short cross bars 29 are further disposed in regard to the sheet length as follows: The inside length of chase, from inside edge of end bar 25a to inside edge of end-bar 25b, is preferably the exact length of the sheet to be worked, and is so represented in Fig. 1. 30 Cross bars 29b, 28b, 29e, divide the chase in the exact center; cross bars 29a, 28a, 29d, divide the chase into quarter-sheet-length sections on the left, and cross bars 29c, 28c, 29f, divide the chase into quarter-sheet-length sections on the right, 35 so that exactly one half of the sheet length is represented on the line 29—29 of Fig. 1.

The cross bars 28, 29 thus form a series of transverse spacing members which serve four distinct purposes: (a) In combination with the adjoining spacing strips, they form margin space, and, in this one respect, only, correspond with the conventional chase assembly; (b) they bear against and rigidly position the head bars 27a, b; (c) they divide the chase structure into twelve 45 sections: four four-page-lock-up groups, and eight two-page-lock-up groups; (d) they provide a bearing for one of the longitudinal sides on each type-page.

It is pointed out that heretofore it has been 50 the invariable custom to determine the imposition of a type-form in a chase by means of spacing material, suitably arranged against the bars of the chase, which may be adaptable to various sheet sizes; in my invention the imposition of the type-form is predetermined by the arrangement of the bars comprising the chase, which is adapted to one specific size. In other words, the conventional method of imposition may cause the folds of the subsequently-printed sheet to register with either the spacing material or the cross bars in the chase structure; in my invention, the folds invariably coincide with the cross-bar structure. In Fig. 1 the cross bars 28, 29 coincide with the "outside" margins.

65 The form of chase shown in Fig. 1 is not intended to be adjustable. The steel bars comprising the chase represented in Fig. 1 (which has been scaled to a sheet size of substantially 30½ x 41 inches) are preferably 1 inch wide and 70 ½% of an inch thick, although, due to the comparatively light quoin squeeze used in locking the type-pages, a much thinner bar may be satisfactorily employed. In practise, the mortised butt joint shown in Fig. 1 appears to be the most desirable but any style of jointing may be used

in assembling the bars, it being manifest that it is not necessary to tie the bars together for portable use, as in the usual type of chase construction and usual mode of handling.

Figs. 3 and 4 show how the cross bars 28a, 29a 5 are prevented from working-up or bulging by the swaged lips 34 of the head bar 27a.

Fig. 11 shows a plan view of the press-bed structure of a cylinder press, in which are represented the register rack 51, the bed bearers 52, 10 bed bearer screws 53, bed furniture (spacing material) 54a, b, c, d, e, chase clamps 55, chase clamp screws 56, ink plate 57, face of press bed 58, distributor-roller rack 59, bed gib 60, all of which are regular equipment. In the carrying-out of the invention, the bars comprising the chase are first assembled on the press bed 58. A strip of bed furniture 54a of the required thickness is inserted between the chase bar 26b and ink plate 57 to position the printing form 20 in reference to the sheet width, and bed furniture 54b between chase bar 25a and bed bearer 52a in similar manner positions the form in reference to sheet length. The chase structure is clamped on the press-bed by the quoins 46 and 25 chase clamps 55, before imposing the type-form elements. The clamping of the chase structure on the bed of a press preliminary to imposing self-contained type-pages therein is a new feature in the art. 30

Thirty-two pages 35 are imposed in the twelve lock-up groups of chase shown in Fig. 1. A layout of sixty-four pages is made by dividing the imposition into twenty lock-up groups, comprising twelve lock-up groups of four pages each and 35 eight lock-up groups of two pages each, in the same relative manner as shown in Fig. 1. A layout of 128 trade-book pages, the page-paper-size of which is generally under 6 x 9 inches, may be imposed on the largest press bed now in use by 40 simply following the same division of sheet space into similar lock-up groups of four and two pages each. Since each unit is accurately self-contained, and the quoin squeeze very light, there is no bulge in the chase bars of such a form. It 45 should be pointed out here that, while the original construction of a chase to very accurate dimensions involves no novelty, the maintenance of accurate chase dimensions under all stresses is a radical innovation in the art. 50

Imposition methods

Since permanently precise chase dimensions are provided by my invention, each item of spacing material for the gutters may be accurately specified in advance of "laying" the first form on the press-bed. All page heads 35a are imposed against the head bars 27a—b. A 3-point strip or "lead" 36 is shown interposed in Fig. 2 between the head bar of chase 27a and end bar 60 41a of type-page 35 in order to provide a "top" margin of 4 picas and 3 points, disposed as follows: from center to edge of head-bar 27a, 3 picas; strip 36, 3 points; end bar, 41a, 1 pica. Obviously, one 6-point strip might be employed against one 65 side only of each head-bar, 27a and 27b, and produce the same result. The strip 36 is preferably swaged at intervals along its longitudinal edge 27, as shown in Fig. 10. The swaged protuberances 37 fit under the lower edge of end bar 70 41a of type-page 35 (Fig. 5) and prevent the strip 36 from working-up during the printing operation.

The "outside" margin gutter is formed by the spacing material 38, 39, 44 placed against the nine 75

transverse bars 28a, b, c; 29a, b, c, d, e, f, and also against the two end-bars 25a, b. Fig. 2 shows adjoining cross bar 29c a strip of 10-point wood reglet 38 bearing pins 40 (Fig. 8) that fit into groove 43 (Fig. 6) of pica strip 39. Projections 37 similar to those shown in Fig. 10 may be swaged in all strips that fit against the end bars 41 or side-bars 42 of type-page 35. Adjoining end-bar 25b is spacing material comprising one strip of pica 39 (Fig. 6), three strips of pica 44 (Fig. 7), and one strip of 10-point wood reglet 38. The lug 45 of strip 44 fits into the groove 43 of strip 39; these complementary strips may thus be assembled in interlocking form to any pica 15 dimension.

The "inside" margin is formed by strip 39 and two expanded quoins 46b. The "foot" margin is formed in two separate assemblies, as clearly shown in Fig. 1. The foot quoins 46a (Fig. 2) 20 are preferably expanded first. If the framed page 35 has been twisted slightly out of shape in handling, as frequently occurs, the expansion of the foot quoin 46a may cause only a partial bearing of end bar 41a against head bar 27a. The two 25 surfaces, however, are brought into complete alignment when the side quoins 46b are expanded. This vertical movement of the type-page is brought about through the rocking movement imparted to the foot quoin simultaneously with 30 the aforesaid horizontal expansion of the side quoins. The well-known Wickersham quoin, United States Patents 496,547 and 1,470,297, is employed for this purpose. The result is substantially the same as if two quoins were first 35 lightly locked at the extremities of foot of page, and the side quoins subsequently expanded. The locking of a book form by means of quoins placed adjacent to the side and foot of each page is a new feature in the art.

40 The framed slug-page described in my United States Patent No. 1,935,668, and shown herein as Fig. 5, may be imposed directly on the press-bed in substantially one-half of the time usually required for the dual stone-and-press-bed lock-up 45 of non-framed type-pages. Manifestly, since transpositions cannot occur in a framed slug-page,

no detailed revision of the assembled form is necessary before actual printing. The initial imposition on the press-bed of a form comprised of self-contained type-pages is a radical deviation from previous methods.

5

Summary

The invention disclosed herein clearly shows how (a) a form comprising a plurality of self-contained type-pages (b) may be originally locked on the press-bed (c) without spreading the bars (d) in a chase divided into lock-up groups wherein (e) each page is automatically aligned against fixed bars and (f) is surrounded by interlocking furniture which cannot work-up. These major 15 features have been thoroughly tested in practical use and have proved of great advantage. The description of the means employed in carrying out the invention is for the purpose of example only and the invention is not limited to any particular form of structure. Many modifications 20 will suggest themselves to the skilled mechanic. Thus, a chase of conventional design may be less advantageously employed for press-bed imposition in the manner herein described and still 25 come within the scope of the claim. Broadly expressed, the essence of the invention resides in the press-bed imposition of a plurality of self-contained slug-pages.

30

I claim—

In combination, a flat press bed and an assembled book-chase structure comprising a plurality of longitudinal head bars 27 dividing the space parallelly within the two outside bars 26 into sections wherein the heads of the type-pages 35 squeeze against the longitudinal head bars 27 by locking means employed at the feet of the type-pages; and a plurality of transverse bars 28, 29 jointing the longitudinal bars 27 at right angles and dividing the space parallelly between the outside bars 25 into sections of two pages' capacity 40 setwise wherein the opposite sides of the type-pages will squeeze against the transverse bars 25, 28, 29 by locking means employed at the sides of the type-pages.

45

WILLIAM H. RITENOUR.
